UNITED STATES PATENT OFFICE.

ALEXANDER BARKLEY HARRIS, OF NEW YORK, N. Y.

BRACING TOOL FOR TENNIS-RACKET FRAMES.

Application filed July 9, 1924. Serial No. 725,093.

To all whom it may concern:

Be it known that I, ALEXANDER B. HARRIS, a citizen of the United States, and a resident of the city of New York, borough of Manhattan, in the county and State of New York, United States of America, have invented a new and Improved Bracing Tool for Tennis-Racket Frames, of which the following is a full, clear, and exact description.

10 This invention has relation to tools and has particular reference to a tennis racket frame bracing tool which is employed for the purpose of stringing a racket, said tool being known to the trade as a billiard. 15 Some of the outstanding objects of the present invention are to provide a tennis racket frame bracing tool or billiard which is so constructed as to render the same readily set or released with respect to the 20 frame; to provide a tool of this character which is capable of being associated with the racket frame by a single workman; which is extremely simple yet strong and durable in its construction; which is highly efficient 25 in its purpose, and which is inexpensive to manufacture and produce.

With the above recited and other objects in view, the invention resides in the novel construction set forth in the following 30 specification, particularly pointed out in the appended claims and illustrated in the accompanying drawings, it being understood that the right is reserved to embodiments other than those actually illustrated herein 35 to the full extent indicated by the general meaning of the terms in which the claims are expressed.

In the drawings—

Figure 1 is a longitudinal sectional view 40 through a tennis racket with the tool in applied position and with parts of the same broken away to disclose the underlying structure.

Fig. 2 is a fragmentary partially sectioned 45 view of the tool when released.

Fig. 3 is a perspective view of the tool removed from the racket.

Referring to the drawings by characters of reference, A designates the handle of a 50 tennis racket having the usual frame B at one end and C designates generally the frame bracing tool or billiard. The tool C consists of a rod or shank 10, at one end of which is carried a rigid jaw 11 and the opposite end 55 of which is threaded as at 12, said threads being cut away longitudinally to provide a

flattened surface 13 for a purpose to be hereafter set forth. A movable jaw 14 is carried by the threaded end 12 and is provided with a bore 15 for the reception of 60 the threaded end, which bore 15 is provided with a longitudinally flattened surface 16 whereby in applying the tool to the racket frame the flattened surfaces 13 and 16 will cooperate to prevent casual turning movement of the movable jaw in order to maintain the jaw 14 in an upwardly projecting position and in alignment with the fixed jaw 11.

In stringing tennis racket frames, it is a 70 known fact that in pulling the longitudinal strings in place, considerable force is exerted in a longitudinal direction on the racket frame so that the side portions of the frame were unduly spread apart or bulged. 75 In order to limit the spreading apart of the side portions of the racket the tool C is devised and the stationary and movable jaws 11 and 14 are inserted respectively within the medial portion of the opposite ends of 80 the frame. In setting the tool in place, the movable jaw after engagement is canted slightly in a longitudinal direction so that the same is wedged or jammed against the threaded end 12 of the rod or shank 10 to 85 set up a binding action which holds the same in place against relative movement irrespective of the amount of force brought to bear on the free ends of the jaws when engaged within the racket frame. In order, however, 90 to provide and insure absolutely against possible slippage, a safety knob 17 is threaded on to the shank 10 between the fixed and movable jaws and after the desired adjustment of the jaws with respect 95 to each other and in engagement with the racket frame, a safety nut 18 is advanced into engagement with the inner end of the bored portion of the jaw 14. When it is desired to release the jaw 14, a releasing nut 100 18 which is threaded on the outer end of the shank 10 is forced into engagement with the bored portion of the movable jaw 14.

From the foregoing it will thus be seen that an extremely simple, inexpensive, yet 105 highly efficient tool for the purpose specified has been provided and it is to be understood that no limitation is made to the precise structural details.

I claim:

1. A tool for bracing tennis racket frames when stringing the same, comprising a

- shank having a stationary jaw member at one end, an apertured movable jaw member carried by the opposite end for relative adjustment toward and away from the stationary jaw member, said jaw members adapted for engagement respectively within the medial portions of the opposite ends of the frame and the apertured portion of the movable jaw member adapted to be canted
- 5 10 when engaged within the frame to frictionally bind upon the shank to retain itself in place, means for positively preventing rocking movement of the movable jaw member when the tool is in engaged position with the racket frame comprising threads on the free end of the shank, and a nut disposed thereon at the inner side of the movable jaw member for advancement against the inner side thereof.
- 15 20 2. A tool for bracing tennis racket frames when stringing the same, comprising a shank having a stationary jaw member at one end, an apertured movable jaw member carried by the opposite end for relative adjustment toward and away from the stationary jaw member, said jaw members adapted for engagement respectively within the medial portions of the opposite ends of the frame and the apertured portion of the
- 25 30 movable jaw member adapted to be canted when engaged within the frame to frictionally bind upon the shank to retain itself in place, means for positively preventing rocking movement of the movable jaw member when the tool is in engaged position with the racket frame comprising threads on the free end of the shank, a nut disposed thereon at the inner side of the movable jaw member for advancement against the inner side thereof, and means for releasing the movable jaw member comprising a nut on the threaded portion of the shank positioned at the outer side of the movable jaw for movement thereagainst to rock the jaw to a

position to release it from its binding position. 45

3. A tool for bracing tennis racket frames when stringing the same, comprising a shank having a stationary jaw member at one end, an apertured movable jaw member carried by the opposite end for relative adjustment toward and away from the stationary jaw member, said jaw members adapted for engagement respectively within the medial portions of the opposite ends of the frame and the apertured portion of the movable jaw member adapted to be canted when engaged within the frame to frictionally bind upon the shank to retain itself in place, and interengageable means on the shank and movable jaw member for preventing casual rotation of the movable jaw with respect thereto whereby to maintain said movable jaw in alignment with the stationary jaw. 50 55 60 65

4. A tool for bracing tennis racket frames when stringing the same, comprising a shank having a stationary jaw member at one end, an apertured movable jaw member carried by the opposite end for relative adjustment toward and away from the stationary jaw member, said jaw members adapted for engagement respectively within the medial portions of the opposite ends of the frame and the apertured portion of the movable jaw member adapted to be canted when engaged within the frame to frictionally bind upon the shank to retain itself in place, and interengageable means on the shank and movable jaw member for preventing casual rotation of the movable jaw with respect thereto whereby to maintain said movable jaw in alignment with the stationary jaw, said means consisting of a flattened face on the shank and a complementary flattened face on the apertured portion of the movable jaw. 70 75 80 85 90

ALEXANDER BARKLEY HARRIS.
